United States Patent Office.

JOHN PELSOR, OF BROOKLYN, ILLINOIS.

Letters Patent No. 72,673, dated December 24, 1867.

IMPROVEMENT IN CHURNS.

The Schedule referred to in these Letters Patent and making part of the same.

TO ALL WHOM IT MAY CONCERN:

Be it known that I, JOHN PELSOR, of Brooklyn, in the county of Schuyler, and State of Illinois, have invented certain new and useful Improvements in Churns; and I do hereby declare that the following is a full, clear, and exact description thereof, reference being had to the accompanying drawings, and to the letters of reference marked thereon, which form a part of this specification. In the annexed drawings, which make a part of this specification—

Figure 1 represents a side view of my churn.

Figure 2 is a plan view of the same.

A, which designates the body of my churn, is quadrate in form, and diminishes in size from bottom to top. Two sides of the churn are made higher than the other two, in order that they may receive the spindle *d*, on which the dasher-staffs *E E* are intended to work. B, which represents the top of the churn, is furnished with three cleats, *f*, in form as seen in dotted lines, fig. 1. Through these cleats the spindle *d* passes, and between which the staffs *E E* can play with a reciprocating motion. *g* represents a series of boards, which penetrate the staffs *E E*, and constitute the dashers of my churn. The boards *g*, it will be seen, by reference to fig. 2, are reduced to half their width on the inner side of the staffs *E E*. On one staff, the lower half of the boards is removed, and on the other staff, the upper half is removed, so that when in motion the several boards can pass each other without impinging. *D* represents a brace, securely fastened to one side of churn *A*, through which a slot is cut to receive the two-pulleys *m* and *n*, as shown in dotted lines, fig. 1. The pulley *m* has its axle secured to the outer side of brace *D* by cleats *h*. The axle of pulley *n* is secured in a similar manner to the inner side of said brace. The axle of pulley *n* extends far enough through brace *D* to admit of the arms *C*, which are securely fastened to the opposite ends of said axle. One of the arms *C* is bolted to the axle at its upper end, and the other at its lower end of the arm, so that the two pitmen to which they are fastened will always move in opposite directions. *H H* represent the pitmen, which are pivoted to the arms *c c* at one end, and made forked at the other end, to receive the staffs *E E*. *I* represents, in dotted lines, the cross-band, which drives the upper pulley *n* when the lower pulley *m* is operated by crank *s*.

It will be remarked that when the pulley *m* is revolving, it will impart a rapid motion to the small pulley *n*; and by the consequent rapid motion of the pitmen *H H*, and of the dashers, the required agitation will be given to the milk.

Having thus described my invention, what I claim, and desire to secure by Letters Patent, is—

1. The staffs *E E*, furnished with dasher-boards *g*, so constructed that the lower half of the boards on one staff will pass the upper half of the board *g* on the other without impinging.
2. The box *A*, the top *B*, the staffs *E E*, the arms *C*, and pulleys *m* and *n*, the whole combined, constructed, and operating substantially as described.

In testimony that I claim the foregoing as my own, I affix my signature in presence of two witnesses.

JOHN PELSOR.

Witnesses:

CHARLES C. BESELL,
C. W. HITE.
